ILLUMINATION LAMP

Nils D. Levin, Columbus, Ohio, assignor to The Jeffrey Manufacturing Company, Columbus, Ohio, a corporation of Ohio

Application October 22, 1929, Serial No. 401,534

10 Claims. (Cl. 240—102)

The invention relates to an illuminating lamp.

Where it is necessary to provide artificial light to facilitate operation of machinery or the like, great inconvenience has been caused by the 5 tendency of lamps providing such light to be broken and put out of commission through the carelessness of operators of machinery, or through the operation of the machinery itself.

For instance, in the case of a mining machine 10 where artificial light is essential, the usual lamp attached to such machinery is not of durable enough construction to long withstand the operation of the machinery, or the liability of workmen throwing tools on top of the machine and 15 against the lamp.

It has also been found desirable in the case 20 of mining machines and the like, to provide a lamp which will throw a beam of light in any direction and, at the same time, provide a shield from the light behind which the operator can stand 25 in order not to be blinded by the glare.

The object of the invention is to provide a lamp which can be placed on machinery of various types where illumination is necessary to facilitate 25 operation of such machine.

Another object of the invention is to provide a lamp of such construction as to be exceedingly strong and durable.

Another object of the invention is to provide 30 a lamp which will throw rays of light in the desired directions.

Still another object of the invention is to provide 35 a lamp which will be cheap to manufacture and yet efficient in every respect.

With these and other objects and advantages in 40 mind, attention is called to the drawing, in which: Figure 1 is a side elevation of the assembled lamp.

Figure 2 is a plan view. 45 Figure 3 is a vertical cross section, and

Figure 4 is a view of the protective screen shield.

Referring specifically to the drawing, in which like numbers indicate like parts, there is provided a base member 1 having ears 2 with apertures 3 therein for securely fastening the device in any suitable place on the equipment with which it is to be used. An insulation block 4 is secured to the inside of the base member 1 and has attached thereto a common lamp socket 5, in which is placed the usual electric light bulb 6. A stuffing box 15, of a design well known in the art, is provided for the passage of a conductor to the lamp socket. The base member is provided with an upwardly extending flange 7 having a groove 8 therein. A plurality of bolts 14 having

shoulders thereon are screw threaded into the outer edge of the base member 1.

A metal cap 10 is provided with a downwardly extending flange 11, having therein groove 12. The metal cap fits upon shoulders on the tops of the bolts 14, and is held securely in place by ordinary nuts. The base and top members are constructed of metal, and have a sufficient cross section to withstand abnormal compression and also radiate heat caused by the illuminating element. 10

Within the grooves 8 and 12 is placed suitable packing 13, and tightly held by said packing is a cylindrical glass globe 9.

To prevent the breakage of the glass, a relatively heavy wire screen 16 is placed around the 15 shoulders 17 and 18 of the base and top members, respectively.

The screen shield may be a complete circle of open work, or it may be made partly of sheet metal, such as is shown in Figure 4, wherein the 20 wire screen 16 is connected by any suitable means to the sheet metal portion 19. Provided at the bottom of the sheet metal portion are a series of holes 20 which, with the use of a sharp pointed tool, quick rotation of the metal part and screen 25 may be had, in order that the rays of light may be cast in the desired direction.

In order to provide for brilliant reflection of the light, the upper side of the base member, the under side of the cap member, and the inside of 30 the sheet metal shield may be coated with white enamel or a phosphorous paint.

In the particular embodiment of my invention herein shown, the base and top members are of 35 circular design, although such circular construction may be departed from.

My invention is not limited to the exact construction herein shown, but is subject to various changes and modifications within the spirit of the appended claims. 40

I claim:

1. In a lamp, a base member having an upwardly extending rib, a top member having a downwardly extending rib, an illuminating element interposed therebetween, independent 45 means to rigidly secure said members to each other, and a plurality of protective means for said illuminating element, the outer of which abuts the outer shoulders of said ribs.

2. In a lamp, a base member having an upwardly extending rib, a groove in said upwardly extending rib, an illuminating element attached to said base member, a top member having a downwardly extending rib, a groove in said downwardly extending rib, means to rigidly secure said 50 55

- base and top members to each other, transparent protective means secured in said grooves, and a rotary protective means abutting the outer shoulders of said ribs.
5. 3. In a lamp, a base member having an upwardly extending rib, a groove in said upwardly extending rib, an illuminating element attached to said base member, a top member having a downwardly extending rib, a groove in said downwardly extending rib, means to rigidly secure said base and top members to each other, transparent protective means secured in said grooves, rotary protective means abutting the outer shoulders of said ribs, said rotary protective means being partly opaque.
10. 4. In a lamp, a base member, an illuminating element carried by said base member, a top member, transparent protective means held between said base and top members and surrounding said illuminating element, and protective means mounted for rotation on said top and base members and having reticular and opaque sections.
15. 5. In a lamp, the combination with a relatively heavy flat base member, of a relatively heavy flat opaque top member spaced therefrom, an illuminating element supported by said base member, transparent protective means between said base member and said top member and completely surrounding said illuminating element, a rotary opaque shutter in substantially vertical position outside of said transparent protective means and between said base member and said top member, the shutter having the shape of a segment of a cylinder and constantly obscuring the illuminating element from a point of view determined by its rotary adjustment while permitting the constant projection of light from the lamp through the complementary segmental portion of the cylinder of which it is a segment, said shutter including a reflector on the inner face thereof, and a plurality of bolts rigidly connecting the top and bottom members.
20. 6. In a lamp, the combination with a relatively heavy flat base member, of a relatively heavy flat opaque top member spaced therefrom, an illuminating element supported by said base member, transparent protective means between said base member and said top member, a rotary opaque shutter between said base member and said top member and outside of said transparent protective means, the shutter having the shape of a segment of a cylinder and constantly obscuring the illuminating element from a point of view determined by its rotary adjustment while permitting the constant projection of light from the lamp through the complementary segmental portion of the cylinder of which it is a segment, said shutter including a reflector on the inner face thereof, means adjacent the peripheries of the base and top members respectively for guiding said segmental shutter for complete rotation, and a plurality of bolts rigidly connecting the top and bottom members.
25. 7. In a lamp, the combination with a relatively heavy flat base member adapted to rest on and slide over a supporting surface, of an illuminating element carried by said base member, a plurality of bolts rigidly connecting the top and bottom members, transparent protective means held by and between said base member and said top member and completely surrounding said illuminating element, and means outside of said transparent protective means to control the projection of light in varying directions, said last-named means including a reflector.
30. 8. In a lamp, the combination with a base member adapted to rest on and slide over a supporting surface, of an illuminating element carried by said base member, means extending through said base member above the bottom thereof for connecting said illuminating element to a source of illuminative supply, an opaque top member spaced above said base member, a cylindrical transparent protective means between said base member and said top member, means for clamping said top member against said transparent protective means and the latter against said base member, and cylindrical protective means mounted for rotation between said base member and said top member outside of and concentrically with said transparent cylindrical protective means, said outer protective means having perforate and opaque segments, the opaque segment of said protective means constantly obscuring the illuminating element from a point of view determined by its rotary adjustment and the perforate segment permitting the constant projection of light from the lamp therethrough.
35. 9. In a lamp, the combination with a relatively heavy flat bottomed base member, of a relatively heavy flat top member spaced therefrom, an illuminating element between said base member and said top member, transparent protective means surrounding said illuminating element between said base member and said top member, adjustable protective means surrounding said illuminating element including an opaque shutter mounted for rotation outside of said transparent protective means, and a plurality of bolts rigidly connecting the top and bottom members.
40. 10. In a lamp, the combination with a relatively heavy flat bottomed base member, of a relatively heavy flat top member spaced therefrom, an illuminating element between said base member and said top member, transparent protective means surrounding said illuminating element between said base member and said top member, adjustable protective means surrounding said illuminating element including an opaque shutter mounted for rotation outside of said transparent protective means, said shutter including a reflector on the inner face thereof, and a plurality of bolts rigidly connecting the top and bottom members.
